TOE CLEAT FOR ROOF SHINGLING OPERATIONS

Wallace E. Johnson, 906 Corning St.,
Red Oak, Iowa 51566

Filed Aug. 1, 1969, Ser. No. 18,507

Term of patent 14 years

Int. Cl. D25—99

U.S. Cl. D54—1

FIG. 1 is a perspective view of my new design for a toe cleat for roof shingling operations.

FIG. 2 is a left side elevational view of my new design, the right side elevational view being a mirror image thereof.

FIG. 3 is a top plan view of my new design.

FIG. 4 is a bottom plan view of my new design.

FIG. 5 is a sectional elevational view taken along line 5-5 of FIG. 1, the sectional elevational view along line 6-6 of FIG. 2 being a mirror image thereof.

I claim:

The ornamental design for a toe cleat for roof shingling operations, as shown and described.
